UNITED STATES PATENT OFFICE.

BLAIR HARDESTY, OF CLIFTON FORGE, VIRGINIA, ASSIGNOR TO LANDIS MACHINE COMPANY, OF ST. LOUIS, MISSOURI, A CORPORATION OF MISSOURI.

WORK-GUIDE FOR SEWING-MACHINES.

1,143,701.

Specification of Letters Patent. Patented June 22, 1915.

Application filed November 14, 1914. Serial No. 872,141.

To all whom it may concern:

Be it known that I, BLAIR HARDESTY, a citizen of the United States, residing at Clifton Forge, Virginia, have invented a 5 certain new and useful Improvement in Work-Guides for Sewing-Machines, of which the following is a full, clear, and exact description, such as will enable others skilled in the art to which it appertains to 10 make and use the same, reference being had to the accompanying drawings, forming part of this specification, in which—

Figure 1 is a top plan view. Fig. 2 is a side elevational view. Fig. 3 is a fragmentary enlarged top plan view.

This invention relates to a new and useful improvement in sewing machines designed especially for sewing leather, and particularly to that class shown in the patent to Pedersen, No. 811,582, dated February 6, 1906.

This present invention is directed particularly to a novel means for adjustably holding or guiding the work while it is being fed 25 through the machine, said means being adjustable during the time that the machine is operated, thus enabling the operator to quickly and easily regulate the machine for different kinds of work without necessitating the stopping of the machine. I have not shown the stitch forming mechanism in the accompanying drawings, as the same forms no part of my invention, and with respect to the awl operating and feeding mechanism, 30 attention is directed to the Blair Patent, No. 1,092,892, dated April 14, 1914, which is herein illustrated.

In the accompanying drawings, 1 indicates a portion of the frame of the machine 40 which is provided with a forwardly extending portion 2 constituting a work table in which the slot 3 is arranged for the awl 4. I deem it unnecessary to describe the operation of this awl feeding and operating 45 mechanism, as the same is fully set forth in the Blair patent before mentioned. Heretofore this work table has been provided with a threaded opening for the reception of a machine screw or bolt carrying a roller 50 or post adjacent the awl slot, and which post constituted a work guide. Posts of different diameters were used for work of different kinds, but it is obvious that when it was desired to change a post of one size for a 55 post of a different size, that the one in posi-

tion had to be removed and the other substituted therefor.

It is the purpose of my present invention to obviate the necessity for removing or substituting one piece for another, and hence I 60 arrange on the work table a guiding post 5 with which coöperates the slotted end of a work guiding member 6, the slot in said work guiding member being inclined to its direction of movement. This work guiding member is preferably in the form of a link whose opposite end is pivotally connected to a crank pin 7 arranged on a notched disk 8. The notches of this disk coöperate with a detent or restraining spring 9, there being a 70 handle 10 connected to the shaft of the disk by which same may be rotated.

As shown in Fig. 1, the work guide is adjusted to its position closest to the awl, but by rotating the disk through the medium of 75 the handle in an anti-clockwise direction, the work guide will be moved away from the awl, the adjustment continuing to the position shown in full lines in Fig. 3. Of course it is understood that this range of adjustment can be increased or diminished as necessity requires, and also that the operating face of the work guide, here shown as beveled, can be modified to suit the character of work to be done on the machine. 80

What I claim is:

1. A work guide for sewing machines comprising a work table, a work guiding member having a slot and pin connection with the table, said slot being at an angle 90 to the line of movement of the member, an actuating member connected for operating the guiding member, and means yieldably engaging the actuating member to hold the guiding member in adjusted positions. 95

2. A work guide for sewing machines comprising a work table, a work guiding member disposed obliquely to the line of travel of the work and having movable connection with the table, an actuating member connected for operating the guiding member, and means yieldably engaging the actuating member to hold the guiding member in adjusted positions. 100

3. A work guide for sewing machines 105 comprising a work table and a work guiding member mounted thereon by a slot and pin connection, said slot being arranged at an angle to the direction of movement of said work guiding member, means for moving 110

said work guiding member, said means being in the form of a disk having a series of teeth, and a spring detent coöperating with said teeth to hold the guiding member in adjusted positions.

4. A work guide for sewing machines comprising a work table, a rotary disk operatively sustained in relation to the table and having a series of teeth, a work guiding member eccentrically pivoted to the disk and having a slot and pin connection with the table, said slot being disposed at an angle to

the direction of movement of the member, a hand lever connected for rotating the disk to adjust the guiding member, and a spring detent coöperating with said teeth for holding the member in adjusted positions.

In testimony whereof I hereunto affix my signature in the presence of two witnesses, this 27th day of October, 1914.

BLAIR HARDESTY.
